US0D1033374S

(12) **United States Design Patent** (10) Patent No.: **US D1,033,374 S**
(45) Date of Patent: ** Jul. 2, 2024

(54) **SECURITY KEYPAD WITH BATTERY BACKUP PACK**

(71) Applicant: **Arlo Technologies, Inc.**, Carlsbad, CA (US)

(72) Inventors: **Scott McManigal**, Newport Beach, CA (US); **Soo Youn Park**, Lake Forest, CA (US); **Eng-Long Goh**, San Diego, CA (US); **Christopher Fonzo**, Carlsbad, CA (US)

(73) Assignee: **Arlo Technologies, Inc.**, Carlsbad, CA (US)

(**) Term: **15 Years**

(21) Appl. No.: **29/882,413**

(22) Filed: **Jan. 13, 2023**

(51) LOC (14) Cl. **10-05**

CLAIM

The ornamental design for a security keypad with battery backup pack, as shown and described.

DESCRIPTION

FIG. 1 is a top, front, right-side isometric view of a security keypad with battery backup pack showing our new design; FIG. 2 is a front elevation view thereof; FIG. 3 is a rear elevation view thereof; FIG. 4 is a right-side elevation view thereof; FIG. 5 is a left-side elevation view thereof; FIG. 6 is a top plan view thereof; FIG. 7 is a bottom plan view thereof; and, FIG. 8 is a bottom, front, right-side isometric view thereof. The broken lines represent unclaimed portions of the design. All of the broken lines form no part of the claimed design.

1 Claim, 8 Drawing Sheets
